UNITED STATES PATENT OFFICE.

JOHN E. BRIELMAIER, OF CHICAGO, ILLINOIS, ASSIGNOR TO THE T. F. PHILLIPS CO., OF DUBUQUE, IOWA, A CORPORATION OF IOWA.

DESIGN FOR AN ALTAR-BOY'S STOOL.

No. 38,276.

Specification for Design.

Patented Oct. 9, 1906.

Application filed July 30, 1906. Serial No. 328,481. Term of patent 7 years.

To all whom it may concern:

Be it known that I, JOHN E. BRIELMAIER, a citizen of the United States, residing at Chicago, in the county of Cook and State of Illinois, have invented a new, original, and ornamental Design for an Altar-Boy's Stool, of which the following is a specification, reference being had to the accompanying drawing, forming a part thereof.

The figure is a perspective view of an altar-boy's stool, showing my new design.

I claim—

The ornamental design for an altar-boy's stool as shown.

JOHN E. BRIELMAIER.
